(57) **CLAIM**

The ornamental design for a security rod, as shown and described.

DESCRIPTION

FIG. 1 is a perspective view of the present invention positioned below a window sill of a security rod showing my new design;

FIG. 2 is a perspective view thereof;

FIG. 3 is a top plan view thereof; and,

FIG. 4 is a front elevational thereof.

The broken line showing is included for the purpose of illustrating and forms no part of the claimed design.
